US00D796325S

(12) **United States Design Patent** (10) **Patent No.:** **US D796,325 S**
(45) **Date of Patent:** **** Sep. 5, 2017**

(54) **CAP FOR A BOTTLE**

(71) Applicant: **IGNITE USA, LLC**, Chicago, IL (US)

(72) Inventor: **Blair Miller**, Chicago, IL (US)

(73) Assignee: **IGNITE USA, LLC**, Chicago, IL (US)

(**) Term: **15 Years**

(21) Appl. No.: **29/535,161**

(22) Filed: **Aug. 4, 2015**

(51) **LOC (10) Cl.** **09-07**

(57) **CLAIM**

The ornamental design for a cap for a bottle, as shown and described.

DESCRIPTION

FIG. 1 is a top perspective view of a cap for a bottle showing our new design;

FIG. 2 is a bottom perspective view thereof;

FIG. 3 is a front view thereof;

FIG. 4 is a right side view thereof;

FIG. 5 is rear view thereof;

FIG. 6 is a left side view thereof;

FIG. 7 is a top view thereof; and,

FIG. 8 is a bottom view thereof.

The broken lines shown in the drawings are included for the purpose of illustrating environmental structure and form no part of the claimed design.

1 Claim, 7 Drawing Sheets
